HINGED BOW

Bernard J. Grenier, Detroit, Mich.

Application January 16, 1946, Serial No. 641,487

1 Claim. (Cl. 124—23)

1

This application relates to hinged bows, such as are used in archery. A hinged bow consists of a bow which is split transversely at the handle. Means are provided for movably but non-detachably connecting the upper and lower limbs of the bow.

It is an object of the present invention to provide a novel and improved hinge for connecting the upper and lower limbs of a split bow. The connecting means herein disclosed will now be described upon reference to the appended drawing.

In this drawing,

Fig. 1 is a front view showing a section of a hinged bow at the handle, with the hinge in place.

Fig. 2 is a view as if from the right of Fig. 1.

Fig. 3 is a view like Fig. 2 but showing the bow with its limbs swung back on each other.

The drawing shows a bow 10 whose handle 11 is split or cut transversely on line 12 to provide upper and lower limbs. On the outer surface of each limb, adjacent to the split, is firmly fastened a plate 14, as by screws 15 whose heads are countersunk in holes of the plate. The plates 14 have their ends spaced a considerable distance from the split line 12 and their ends are formed with numerous identical teeth adapted to interfit or mate with similar teeth formed at the ends of a third plate 16 which straddles the split line 12 or lies over it. When the third plate 16 is so disposed with respect to the plates 14 that the interfitting or mating teeth at the ends of the third plate 16 mate or interfit with the teeth at the ends of the two plates 14, hinged pins 18 extending transversely of the three plates may pass through aligned apertures of the teeth for pivotally connecting the three plates at their ends to one another and thus form a three element hinge.

When the bow is extended, and the parts are properly mounted and interfitted, the three plates together form an uninterrupted smooth face hinge overlying the outer surface of the bow and covering the split 12.

Thus, the three plates and their hinge pins lie flat against the bow, presenting no bumps or bulges to interfere with or impair proper operation and shooting.

2

If desired, although it is not necessary, a piloting means such as a pilot pin 21 may be secured to one of the limbs as by being threaded into it, to seat itself in a piloting notch 22 of the other limb, and thus help in locating the two limbs as they are moved to each other so as to be connected so as to form a complete extended bow.

In addition, if desired, a thin rubber cushion 23 may be secured adhesively to one of the limbs 10 to prevent noises from arising due to the contact of the butt ends of the limbs, during shooting.

When the bow is collapsed as indicated in Fig. 3, the intermediate plate 16 separates the limbs from each other and yet maintains the two limbs in relative assembly.

Now having described the hinged bow herein disclosed, reference should be had to the claim which follows:

I claim:

20 A hinged bow split transversely at the handle and having upper and lower limbs engaging at the split line, hinge means for connecting the upper and lower limbs comprising two small flat plates immovably fastened to such limbs on the outer surface thereof, and a third plate connected at its ends to the ends of the first named two plates by transverse hinge pins, the first two plates having their adjacent ends remote from the bow split, with the latter being between such adjacent ends, and the third plate straddling such split, whereby a three element hinge is formed by the three plates, with the third plate covering the bow split, the three plates being formed so that, when the bow is extended for shooting, they form an uninterrupted smooth faced hinge overlying the outer surface of the bow.

BERNARD J. GRENIER.
